Primary Examiner—Alan P. Douglas*Assistant Examiner*—Lavone D Tabor*Attorney, Agent, or Firm*—Holland & Knight LLP**[57] CLAIM**

The ornamental design of a set of bristles for a toothbrush, as shown and described.

DESCRIPTION

FIG. 1 is a perspective view of my ornamental design for a set of bristles for a toothbrush;

FIG. 2 is a bottom plan view thereof;

FIG. 3 is a top plan view thereof;

FIG. 4 is a side elevational view thereof, the opposite side being a mirror image; and,

FIG. 5 is an end view thereof, the opposite side being a mirror image.

The structure shown in phantom or broken lines in the FIGs. forms no part of the claimed design and is included only to illustrate an environment.
